MOTOR-DRIVEN HAND TOOL

William M. Emery, Shaker Heights, Ohio, assignor
to The Rotor Tool Company, a corporation of
Ohio

Application November 23, 1942, Serial No. 466,601

3 Claims. (Cl. 51—170)

My invention refers to improvements in power driven hand tools with special attention to grinders, nut setters, drills, and the like where the tools are of such horsepower that they develop substantial reactive torque which must be resisted by the operator. This includes such tools that for efficient or convenient operation and usually for support, the handle is positioned substantially axially or parallel thereto.

This invention bears some similarity in field and objects to that covered in my Patent #2,301,264, to which reference will be made. My previous invention, although very helpful with many classes of applications, has certain limitations which are overcome in my present invention, principally by avoiding close indexing between the forearm of the operator and the wheel guard and allowing for varying the angle between the guard and the work by the flexing of the wrist.

With grinders, a limit has been found above which in the past it has been inefficient to increase the horsepower and the torque because of the inability of the operator to resist the reactive torque by gripping the straight or axial handles without excessive fatigue. In fact, the majority of the fatigue in the use of such tools is directly traceable to finger, hand and wrist fatigue, so much so that in continuous operation the operator seldom presses sufficiently upon the work to utilize the full horsepower capacity of the tool or to secure maximum removal from the work being ground. The work accomplished is further reduced by necessary rest periods. Furthermore, if the wheel grabs while grinding the inside radius of a hole the operator is often unable to hold the tool and frequently suffers injury.

Some years ago spade handles were used on such tools. A spade handle consists of a handle like that of a spade. It has a hand contacting portion substantially perpendicular to and across the axis of the tool and connected to the tool by rigid bars integral to each end of the handle. They have been largely abandoned after many hands, especially thumbs, were injured when the wheel grabbed. The spade handle provided insufficient leverage to resist the stalling load of the motor and when this occurred the operator was often unable to disengage his hand before injury.

The so-called straight or axial handles shown in my Patent 2,301,264 are the standard conventional handles used today and their axial position is more convenient for most grinding, but in the

last five years during which such handles have been used with large tools, no method has been advanced by any other that successfully overcomes the fatigue problem that so limits the production and horsepower torque capacity of this type tool. My previous invention by longer leverage places the reactive torque largely midway on the forearm of the operator. In my present invention the reactive torque is applied through my torque arrestor lever to the lowest point of the forearm namely the bony structures of the forearm which in part constitutes the wrist joint and the heel of the hand adjacent thereto, although I do not so limit the sphere of my invention. More specifically, the reactive torque presses my torque arrestor lever against the hypothenar eminence of the hand adjacent to the wrist when the handle is normally grasped. The conventional straight handles when normally grasped cross the palm of the hand distal (that is away from relative to the body) to both the thenar (that is the thumb) eminence and the hypothenar eminence. Thus my torque arrestor lever substantially doubles the lever arm as compared to conventional axial handles resisting the reactive torque. This would of course reduce the friction grip required to hold the handle 50%, if the handle were substantially round.

My invention goes still further by providing an irregular shape which will not turn easily in the hand, so that the hand need not be gripped so tightly and the blood may circulate freely through the fingers. Also much of the wrist strain and fatigue is eliminated, because the leverage at the wrist is reduced to a minimum by applying the pressure from the reactive torque to the hypothenar eminence adjacent to the wrist. There is no muscular pad more adequate and adjacent to the wrist to receive this reactive torque thrust. Accordingly, I have as an object of my invention an adjunct to axial handles used with the type of tools described consisting of novel projecting lever arm which provides greater moment for resisting the reactive torque of the tool without materially increasing the perimeter of that part of the handle normally gripped by the hand and more particularly the thumb and fingers. It is known that that there is a definite limit to the size of the periphery or diameter of a bar which can be comfortably and tightly gripped by a normal hand, and such limited circumference does not allow sufficient leverage to resist the reactive torque in many cases, a diameter in the neighborhood of 1 3/4 inches has been generally recognized in this field as a comfortable handle

size. I have found that a range of one to two and one-quarter inches is possible, although the extreme sizes are much more fatiguing where reactive torque must be resisted.

Another object is to provide an abutment or lever arm projecting from a hitherto practically unused and ungripped portion of the handles of the class of tools already described, said lever arm contacting the proximal end or portion of hypothenar eminence of the operator's hand adjacent to the wrist in a manner to form such a steep cam relationship as to effect not more than a minor resultant tending to open the hand or to act against the muscles maintaining the grip thereon.

Another object is to relieve the fingers, hand and the wrist of the operator from much of the fatigue incident to resisting the torque reaction of the motor by applying said forces more directly to the wrist and more adjacent to the forearm and to a muscular mound more adapted to receive them without fatigue or discomfort.

Another object is to increase the hourly production of the operator by reducing his or her fatigue and also by utilization of the maximum horsepower capacity of the tool and by the increase in the horsepower capacity and also by allowing for the efficient use of tools of greater horsepower and torque.

Another object is to secure many of the advantages of my invention regardless of whether the wheel end handle or its equivalent is held with the left or right hand and the other handle held with the other hand.

Another object is to prevent the tool from twisting in and away from the hands of the operator if and when a stalling load is suddenly applied such as by the work grabbing the wheel or cutting tools.

Also to provide a "torque arrestor lever" as I will hereinafter call an embodiment of my invention that will in no case hamper the release of the tool by the operator in the case of an emergency.

Other objects are to increase the productivity and metal removing capacity of portable tools without increasing operator labor and to reduce the labor of handling many portable tools, so that war workers such as women, who have not sufficient hand strength to handle many tools now on the market, can take over more types of this work.

Further objects and novel features of my construction will be apparent from the following specifications and claims when considered together with the accompanying drawings in which:

Fig. 1 is a side elevation of a conventional electric grinding tool to which has been added embodiments of my invention. The wheel end handle is grasped with the left hand and the other handle with the right.

Fig. 2 is a top elevation of Fig. 1 with the hands omitted.

Fig. 3 is an end view of Fig. 1 substantially as indicated by line 3—3 of Fig. 1.

Fig. 4 is view from the other end of Fig. 1 substantially as indicated by line 4—4 of Fig. 1, held in the left hand.

Fig. 5 is a top or plan view of a spindle end handle suitable for a reversible motorized tool to which an embodiment of my invention has been added.

My invention is not necessarily limited to the embodiments or proportions shown in the draw-

ings or to the specific type of motorization or tool selected for illustrative purposes.

In Fig. 1 I show, as an example, the wheel end or work spindle handle 11 of a portable grinder 5 powered by a 180 cycle induction electric motor mounted in a frame or housing 12 of approximately 2 horsepower under average working conditions but having a stalling torque equivalent to double the working torque. The speed of the 10 grind wheel 9 is geared down to 4000 R. P. M. which at a 2 horsepower load results in a torque of approximately 31.5 inch pounds to be resisted by the operator by gripping two handles such as a wheel end handle 11 or live end handle 20 15 which has a diameter of approximately 1½ inches and is positioned substantially parallel to the axis of the motor in housing 12.

This means that while working at full capacity the operator must constantly resist 42 pounds 20 torque at the surface of the gripping handles. In an effort to prevent the tool from turning in his hand, he must often grip it so tightly that the circulation of blood to his fingers is so restricted as to further exaggerate his fatigue.

Under stalling conditions, because the motor 25 is a substantially constant speed induction motor, the stalling reactive torque in the example set forth would be about 63 inch pounds or 84 pounds on the surface of the handle to be resisted by the grip of the operator. If the wheel grabs, the tool is often wrenches from the operator's hands suddenly and without warning and he cannot contact the push button switch 10 to stop the motor while the tool is revolving. Fear that the stalling 30 power, which without my invention is practically irresistible, might suddenly occur, keeps the operator tense and his muscles stressed. The fatigue to the operator's fingers, hands and wrists resisting such a force, in such a manner is 35 obvious.

While it might seldom be practical for a woman to operate a tool of the size described, the same 40 thing applies proportionately to smaller tools and it is obvious that in all events it will be possible for such an operator to use a tool equipped with my invention possessing at least twice the power of the maximum size tool which she could use without the benefit of my invention, because as 45 previously said my invention more than doubles the lever arm. Also with a substantially round axial handle such as is conventionally used, the grip is largely a matter of friction whereas with my torque arrestor lever a positive abutment 50 largely independent of the surface being gripped is provided to resist the turning of the handles 55 in the hand, as I will now show. This reduces the muscular strain of operation by substantially 75%. Fatigue is also due to the distance between the axis of the handle and the axis of the 60 wrist joint. By abutting my lever more adjacent to the wrist I materially reduce this distance and reduce accordingly the strain on the muscles controlling the wrist movement.

The forward torque arrestor lever 15 arises 65 from the mid portion of the wheel end handle as seen in Fig. 1, sloping up as shown to blend with the gear housing 16. The torque arrestor lever 15 offers a surface to contact with the proximal end or portion of hypothenar eminence of the hand of the operator substantially normal to the tangent of the cylindrical surface of the handle 11 or it can be described as having a steep cam relationship with the hand of the operator 70 which effects only a minor resultant of forces tending to open the gripped hand of the operator. 75

In Fig. 2 it will be seen that it is set at an angle of about 20° to the axis of the handles so that it can be said that it is set at a helix angle on the handle or work spindle 13 of the tool which passes through handle 11. When looking at the wheel, as shown in Fig. 3, and substantially as it would be viewed by an operator in a normal operating position, the wheel usually turns clockwise as shown, or right hand, then the torque arrestor lever 15 is set at a right hand helix angle. If the wheel (or work spindle 13) turned counter-clockwise then the helix angle of the torque arrestor could be left hand such as 17 Fig. 5. On a reversible tool, then both angles would be used so that the combination of both helix angles combining would create a wedge torque arrestor lever 15 and 17 with its apex pointed toward the grind wheel or metal cutting end as viewed from the top as in Fig. 5. This construction is included in my invention.

Fig. 3 shows the torque arrestor lever 15 pressing against the hypothenar eminence of the operator's left hand and approximately adjacent to the wrist joint of the forearm sometimes popularly called the heel of the hand. When the wheel as shown in Fig. 3 turns clockwise the reactive torque tends to turn the handle 11 counter-clockwise to do this, so that the torque arrestor lever 15 prevents the handle 11 from turning in the hand of the operator even though his grip is materially relaxed compared with the necessary required tightness if the torque arrestor abutment 15 were absent.

Fig. 1 also shows that the circumference or perimeter of the part actually gripped is not increased but additional leverage is provided by the torque arrestor abutment pressing against the hand heel or wrist joint without making the size of the gripped part uncomfortably large. Figs. 1, 3 and 4 also show that in gripping any conventional handle of reasonable and comfortable size that there is a normally unused portion of the periphery beyond the ends of the third and little fingers. From this normally unused and uncontacted portion of the handle I project my torque arrestor levers 15 and 21.

Such tools as grinders are used by some operators holding the wheel end handle in the left hand as shown in Fig. 1 and other operators hold the wheel end handle with the right hand. Since the direction of revolution of the wheel 9 is uniform it is obvious that in the latter case the torque arrestor lever 15 will tend to turn away from the heel of the right hand if so held and accordingly in this case would not provide as much benefit in holding the tool in this way as when handle 11 is held in the left hand.

To provide the maximum benefits of my invention under conditions where the hands are reversed left and right from the way shown in Fig. 1, I have also applied my invention in the form of a second torque arrestor lever 21 to the rear or live handle 20 in a modified form, as will be seen in Figs. 1, 2 and 4.

When grinding with a tool having the conventional right hand direction of rotation which is held with the right hand gripping handle 11 and the left hand gripping handle 20, then the torque arrestor lever 21 will be pressed by the reactive torque of the motor against the heel or hypothenar eminence of the left hand adjacent to the wrist joint.

It will be noted from this explanation that when the wheel is rotated in a clockwise direction as shown in Fig. 3 then the left hand resists

the torque arrestor abutment 15 or 21, as the case may be, and if the direction of rotation was reversed then the right hand resists the torque arrestor abutment 17 or 21, regardless of which hands hold the handles 11 and 20, so long as the thumbs of both hands are toward the wheel or work spindle as they customarily are.

It will be seen that in the drawings that the switch 10 is always conveniently located for actuation by the thumb or first finger and I have invented means to greatly assist the resistance of torque reaction in a portable tool without any encircling or other means which might catch or strike the fingers, hands, or body of the careless operator or which might interfere with the sudden release of the tool by an operator in event of an accident.

In this application where I refer to the grind wheel it should be understood that I mean any abrasive polishing, metal cutting or working tool or other type work spindle.

It also should be understood that it is in the realm of my invention to make either or both torque arrestor lever 15 and 21 either as an integral part of handles 11 or 20 respectively or as a separate and removable attachment thereto or with one of them integral with its handle and the other detachable and/or adjustable angularly relative one to the other.

30 The wheel guard 22 is clamped by bolts 23 to the wheel end handle 11 so that it can be set on the handle at any convenient angle about the tool axis relative to the torque arrestor lever 15. As seen in Fig. 1 the wheel guard does not completely cover the wheel 9.

Bolts 26 have a common bolt circle radius likewise bolts 27 so that the wheel end handle with torque arrestor abutments 15 can be set at various angles to handle 20 with torque arrestor abutment 21. Other means to accomplish this indexing of the guard 22 and handles 11 and 20 are well known in the art and may be substituted without departing from the spirit of my invention such as attaching torque arrestor abutment 21 through association with the thread nipple 25.

45 Accordingly I claim:

1. A manually portable unit including the combination of a motor, a shaft rotatably driven thereby, a rotary work device attached to said shaft, a handle having a substantially longitudinal axis positioned sufficiently adjacent to the line of the axis of said shaft and sufficiently parallel thereto to cause said handle to be turned principally about its said longitudinal axis by reactive torque incident to the motor acting to revolve the work device, and a lever predominantly projecting from only one side of a portion of said handle and adapted to be pressed by said reactive torque against the proximal portion of the hypothenar eminence of a hand grasping said handle and to thereby resist the turning of said handle and tool unit in said grasped hand under said reactive torque primarily by abutment with said proximal portion of the hypothenar eminence of said hand in contra-distinction to friction therewith.

2. In a manually portable unit including the combination of a motor, a shaft rotatably driven thereby, a rotary work device attached to said shaft, a handle having a substantially longitudinal axis positioned sufficiently adjacent to the line of the axis of said shaft and sufficiently parallel thereto to cause said handle to be turned principally about its said longitudinal axis by reactive torque incident to the motor acting to

revolve the work device, and a lever projecting from one side of a portion of said handle and adapted to be pressed by said reactive torque against the hypothenar eminence adjacent to the wrist of a hand grasping said handle and to thereby resist the turning of said handle and tool unit under said reactive torque primarily by abutment with said portion of the hypothenar eminence of said hand in contra-distinction to friction therewith.

3. A manually portable unit including the combination of a motor, a shaft rotably driven thereby, a rotary work device attached to said shaft, a handle having a substantially longitudinal axis positioned sufficiently adjacent to the line of the axis of said shaft and sufficiently parallel thereto to cause said handle to be turned principally about its said longitudinal axis by re-

active torque incident to the motor acting to revolve the work device, a lever predominately projecting from one side of a portion of said handle and adapted to be pressed by said reactive torque against the proximal portion of the hypothenar eminence of a hand grasping said handle and to thereby resist the turning of said handle and tool unit under said reactive torque primarily by abutment with said proximal portion of the hypothenar eminence of said hand in contra-distinction to friction therewith, said point of abutment of said lever with said hand being nearer the wrist and further from the axis of said handle thereby increasing the leverage of the hand on the tool and reducing the leverage of the tool on the hand.

WILLIAM M. EMERY.
